(57) **CLAIM**

The ornamental design for a hand sewing needle having periodic markings, as shown and described.

DESCRIPTION

FIG. 1 is a top view of a hand sewing needle having periodic markings showing my new design, the bottom view being a mirror image;

FIG. 2 is a right side view thereof, the left side view being a mirror image thereof;

FIG. 3 is a front view thereof;

FIG. 4 is a rear view thereof; and,

FIG. 5 is a top-rear perspective view thereof.

The features shown in or surrounded by broken lines in the various Figures are for illustrating environmental structure and form no part of the claimed design.
